UNITED STATES PATENT OFFICE.

JOHN E. PECKENPAUGH, OF CEDAR RAPIDS, IOWA.

WINDOW PLATFORM.

Application filed July 21, 1926. Serial No. 123,900.

This invention relates to platforms such as are used by window washers and others operating on the outside of windows. The object of the invention is to provide a convenient, portable and serviceable platform for such uses, special attention having been given to such a construction as will render the platform perfectly safe.

The nature of the invention is fully disclosed in the description and claims following, reference being had to the accompanying drawing, in which:—

Fig. 1 is a side elevation of a platform embodying the invention as in use but with the nearer bearing-block removed, the window parts being shown in section. Fig. 2 is a fragmentary view showing a part of the floor, sill and supporting parts on section lines 2—2 and 2^a—2^a, of Fig. 1, looking toward the left. Fig. 3 is a plan view of the platform in window position, but collapsed.

In the drawing, the numeral 5 denotes the wall of a building surrounding a window opening, and provided with a stone sub-sill 6. In the opening is fixed a window frame 7 provided with the usual sill 8. In Fig. 1 the casing 9 is shown as of a simple flat type, while in Fig. 3 the casing is of a molded type, shown in section.

A pair of sills 10, preferably of T-iron, is bent at 10^a to form uprights 10^b. To the upper ends of these uprights or standards is secured a pair of bearings 11, which are themselves connected by a tube 12. The long, tubular bearing so formed carries a pair of telescoping rods or shafts 13, which may be secured in any desired position by thumb-screws 14. To the outer ends of the shafts are securely attached bearing-blocks 15 adapted to make contact with the inside wall of the building adjacent to the window casing. The blocks are preferably rectangular, and with their supporting shafts off center, whereby the narrower extensions of the blocks may be used when the casings are thin and flat, as in Fig. 1, and the wider extensions when the casings are of the thicker, molded type. The edges of the blocks are shod with rubber, or the like non-abrasive material, to prevent the marring of inside walls.

On the same shafts are mounted abutment plates 16, slidably on the shafts, and secured in any desired position by thumb-screws 17. In practice the bearing-blocks are set close

to the outer edges of the casings, and the abutment-plates against the jambs or window stops, as shown in Fig. 3. This serves to hold the platform rigidly against any possible sidewise movement, such as might be terrifying, if not actually dangerous.

To the upper faces of the sills is bolted the floor 18, herein shown as wooden boards or planks set crosswise. The standards are reinforced by diagonal braces 19 bolted thereto and to the sills.

The depending webs of the sills are pierced with bolt-holes 20, and by means of bolts 21 depending brackets 22 are secured adjustably to the sills. These brackets abutting on the outer faces of the stone window sills serve as strong counter-bearings to the bearing-blocks inside, to give a cantilever support to the platform.

Below the sills, near the upturned standards, foot-blocks 23 are attached, as by lag-screws 24 and wood-screws 25. The blocks are shod with a suitable yielding material, such as sheet rubber, 26, to protect from abrasion the window sill on which the foot-blocks rest.

To protect the operator from falling off the platform, it is provided with a railing which forms a barrier on the three outer sides of the platform. Four uprights, 27 and 27^a are pivoted at their lower ends to brackets 28 bolted to the platform and sills. A cross rail 29 connects the two outer standards rigidly, being welded thereto. These and the inner standards are connected by cross rails 30, to which are welded stud-blocks 31 forming pivots for the ends of the cross-rails. The inner standards are similarly provided with pivotal sleeves 32, which carry sliding brace-rods 33 hinged to the uprights 10^b at 34. Terminal heads 33^a limit the outward movement of the railing by contact with the sleeves. Its movement in the other direction is prevented by thumb-screws 35. The whole forms a railing which may be folded down on the platform, when not in use, and thus occupy little space in handling and transportation. When erect, as in Fig. 1, it is a safe and rigid barrier against stepping off the platform. In practice the railing standards are made of tubular material, and to give additional height to the railing a supplemental railing is provided, having posts 36, cross-rail 37, and pivoted side-rails 38. The posts engage the lower

110

railing standards telescopically, and may be secured at any desired height by means of thumb-screws 39.

To erect the platform, the railing is preferably left in collapsed position, as in Fig. 3, until the platform is in position, as thus the overhanging weight is reduced. For greater convenience the brackets 22 may, by measurement, be adjusted to their proper position before the platform is put through the window, though such adjustment may be made thereafter, if desired. The bearing-blocks 15 are set to the right distance apart, when the platform may be safely thrust through the window and settled to working position. The abutment plates 16 are then set against the window jambs and the railing raised and fastened, when the platform is ready for use, with entire certainty as to its dependability.

Having thus described my invention, I claim:

1. In a window-platform, the combination of a pair of sills, a connected flooring, uprights rising from the inner ends of the sills, a connecting tubular bearing, shafts carrying wall bearing blocks mounted adjustably in said tubular bearing, foot-blocks to rest on the window sill, and brackets secured adjustably to the sills beneath, the sills being pierced with series of bolt-holes, and the brackets being secured by said bolts.

2. In a window-platform having supporting means substantially as described, a protective railing, comprising a plurality of side

standards, the outer ones rigidly connected by a cross-rail, side-rails pivotally connecting with the standards, sleeves pivoted to the inner pair of standards, and brace-rods pivoted to the platform supports at one end, 40 and slideable in said sleeves, with heads to prevent detachment therefrom, and means for preventing slippage of the sleeves on the rods.

3. In a window-platform having sills 45 with upstanding inner uprights and a connected flooring, a protective railing, comprising a plurality of side uprights, floor brackets to which the uprights are pivoted, a connecting cross-rail for the outer pair of 50 uprights, side rails pivotally connecting inner and outer uprights, and side braces pivoted to the sill uprights and slideably connecting with the railing, with means to limit the outer movement of the railing, and to 55 regulate its movement inwardly.

4. In a window-platform, a protective railing, comprising tubular standards pivotally connecting with the platform at their feet, 60 pivotal side rails, braces pivotally connecting with the platform at their inner ends, and slideably with the railing at their outer ends, and a supplemental railing composed of posts telescoping in the tubular standards, and provided with a cross-rail and pivotally connecting side-rails, with means for holding the supplemental railing at any desired height.

In testimony whereof I affix my signature.

JOHN F. PECKENPAUGH.
